UNITED STATES PATENT OFFICE.

ANDREW TURNBULL MACCOY, OF BOSTON, MASSACHUSETTS.

CONTINUOUS BOILER-FEEDER.

SPECIFICATION forming part of Letters Patent No. 592,062, dated October 19, 1897.

Application filed February 18, 1897. Serial No. 624,017. (No model.)

To all whom it may concern:

Be it known that I, ANDREW TURNBULL MACCOY, of Boston, in the county of Suffolk and State of Massachusetts, have invented a new and useful Continuous Boiler-Feeder, of which the following is a specification, reference being had to the accompanying drawings, in which—

Figure 1 is a top plan view of my new boiler-feeder, intermediate portions of the water-cases being broken out, as indicated by waved lines. Fig. 2 is a side elevation of what is shown in Fig. 1; and Fig. 3 is a central sectional elevation on line 3-3 of Fig. 1 and at line 3-3 of Fig. 2, viewed from the geared side of the apparatus. Fig. 4 is an enlarged sectional detail of the valve which controls the passage between the piston-cylinders and of adjacent parts. Fig. 5 is a central sectional view showing a modification wherein the valve-controllers are in the form of floats instead of in the form of tanks.

The object of my invention is to produce an improved, continuously-operating boiler-feeder; and my invention consists in the combination of water-cases and independent piston-cylinders and pistons which operate a valve controlling alternately the steam-inlet to each water-case, with valve-controllers mounted within said water-cases and automatically operating a valve which controls conduits alternately open from a piston-cylinder to the boiler feed-conduit, the water-cases being provided with water-inlets, and also with water-outlets communicating with the boiler feed-conduit, by means of which the boiler is continuously fed by gravitation from either one or the other of the water-cases.

In the drawings illustrating the principle of my invention and the best mode now known to me of embodying that principle, A and B are independent piston-cylinders, and C and D are independent water-cases. G is an oscillating valve controlling a conduit between piston-cylinder A and boiler feed-conduit g, and also between piston-cylinder B and said conduit g.

H is an oscillating valve in the form of a lateral extension from walking-beam p, one arm of the walking-beam being provided with a loosely-jointed link I and the other arm being provided with a loosely-jointed link J.

Link I is loosely pivoted to piston Z in piston-cylinder A, and link J is loosely pivoted to piston Y in piston-cylinder B. The oscillating valve H is mounted in the path of steam-inlet conduit K, this steam-inlet conduit K communicating with the steam-conduit S, which opens into the upper portion of water-case D. Steam-inlet conduit K is also in communication with steam-conduit U, which opens into the upper part of water-case C. Valve H is provided with a steam-passage R, which permits communication of conduit K and conduit S when it is in line therewith. The valve H is also provided with an independent steam-passage T, whereby the conduit K and the conduit U are put into communication when the passage T is in line with the conduits K and U. Conduits S and U are also adapted to communicate alternately with exhaust-conduit X, discharging through the exhaust-port W. When the valve H is in the position shown in Fig. 3, steam-passage R and the steam-inlet conduit K are in communication with conduit S, leading into the water-case D, and at this time the independent passage T of the oscillating valve H connects the steam-conduit U with the exhaust-conduit X, as shown. When the valve H is in position to bring steam-passage T between conduits K and U, steam-passage R connects the steam-conduit S with the exhaust-conduit X, as will be readily understood from the drawings.

The valve H is preferably in the form of a truncated cone and the steam-passages R and T are separated one from the other by a solid central portion of the valve. The oscillating valve G is also preferably in the form of a truncated cone and is formed with water-passages k and j. When the parts are in the position shown in Figs. 3 and 4, the conduit-section h connects piston-cylinder A with the water-passage j in valve G, the passage j then communicating with the conduit g. The solid-metal part of valve G then prevents communication between conduit-section h and the conduit-section i, leading to piston-cylinder B. These conduits or conduit-sections h and i never communicate one with the other, but each leads from a piston-cylinder to the valve G and the conduit g and exhaust V. When the valve is oscillated its

full stroke, the water-passage *j* is carried out of line with conduit-section *h* and conduit *g* and the passage *j* is brought into line with conduit-section *i* and the conduit *g*. This conduit *g* leads into the boiler feed-pipe *N*. The upper portion of the boiler feed-pipe *N* is formed with an enlargement *N'*, which is provided with an interiorly-opening check-valve *o*, controlling communication between the boiler feed-pipe *N* and the water-outlet conduit *L*, which opens into water-case *D*. The enlargement *N'* is also provided with another interiorly-opening check-valve *n*, which controls communication between boiler feed-pipe *N* and the water-outlet conduit *M*, opening into water-case *C*.

The water-supply pipe *O* is provided with two branches *P* and *Q*, branch *P* opening into water-case *D* and provided with a valve-casing *m*, containing a check-valve *m'*, opening toward the water-case *D*. The branch *Q* is provided with a valve-casing *l*, which contains a check-valve *l'*, that opens toward the water-case *C*.

Tank *E* already referred to is carried by a rocker-arm *a*, being loosely jointed thereto near its outer end at *a'*. At its other or butt end it is splined or otherwise secured to a shaft *a²*, journaled in a stuffing-box *a³*, (shown in Fig. 1,) mounted in the side wall of water-case *C*. This shaft *a²* is provided with a gear *c*, fastened rigidly on said shaft. The tank *F* is similar to the tank *E* and is similarly attached to the outer portion of a rocker-arm *b*, mounted on its shaft *a²*, mounted in its stuffing-box *a³*, and provided with a fixed gear *d* similar in all respects to the gear *c*. The gears *c* *d* on these rocker-shafts *a²* *a²* mesh with a gear *e*, fixed on the journal *e'*, mounted in a suitable support *e²* (shown in Fig. 2) from the side of the apparatus. This gear *e* in turn meshes with a segment-gear *f*, which is fixed on the stem *f'* of oscillating valve *G*.

Referring now to the operation of my new boiler-feeder: Supposing the apparatus to be free from water and steam and that the tanks *E* and *F* are in the positions shown in Fig. 3, steam and water may be simultaneously or separately admitted. Supposing the steam to be first admitted (conduit *g* being filled to valve *G* through boiler feed-pipe *N* with water from the boiler and under the pressure therein) it will flow in through conduit *K*, steam-passage *R*, and steam-conduit *S* into case *D* and will close valve *m'*, so that water cannot flow into water-case *D*. Water being turned on it will then flow, from a source of supply, through pipe *O*, past valve *l'*, through water-inlet *Q*, into case *C*. It is to be noted that the tanks *E* and *F* are filled with water at the outset in any appropriate manner and are always kept so filled by the condensation of steam or the inflow of water in the cases *C* and *D*. When water flows into water-case *C*, it approximately neutralizes the weight of the tank *E*, which is balanced by the filled tank *F*. Consequently the weight

of the tank *F* will cause it to descend in case *D*, and as it descends the force of gravitation is transferred through the gears *d*, *e*, and *c* to lift the tank *E* toward the upper part of water-case *C*—that is, to about the water-level of tank *C*—as water flows in through conduit *Q* and rises in tank *C*. This movement of the gears causes segment-gear *f* to oscillate valve *G* and bring water-passage *j* into line with water-conduit section *i* and conduit *g*, thereby carrying passage *k* into communication with conduit-section *h* and exhaust-passage *V*. At this time water from the boiler, at boiler-pressure, being in conduit *N* and conduit *g*, flows through the water-passage *j* in valve *G*, entering conduit-section *i* and flowing under the piston *Y* in piston-cylinder *B*. The piston *Y* is thereby moved upwardly and the valve *II* is thereby rocked to bring the steam-passage *T* into line with the steam-inlet pipe *K* and the steam-conduit *U*, which discharges into the upper portion of the water-case *C*. By this time case *C* has become filled with water, and steam-pressure on its surface causes valve *l'* to be seated. The last-mentioned movement of the valve *II* brings the passage *R* into communication with the steam-conduit *S* and the exhaust-conduit *X*, the piston *Z* being moved toward the bottom of the piston-cylinder *A*.

As above stated, the water-case *D* has received the boiler-steam, and the steam is now exhausted through conduit *S*, steam-passage *R*, and exhaust-conduit *X* and exhaust *W*. The exhaustion of the steam in water-case *D* permits water to flow past check-valve *m'* into the water-case *D*, and at the same time the water begins to flow by gravitation (the apparatus being placed above the water-line of the boiler) past check-valve *n* and through the boiler feed-pipe *N*. This brings the parts into the position shown in Fig. 3, wherein piston-cylinder *A* is shown filled with water and the water-case *D* filled with water to its level, water being shown in the enlargement *N'*, conduit *M*, and to the low-water level of the case *C*. Without interruption, as tank *F* reaches its uppermost position, the mechanically-regulated water-passage *j* is brought by the rotation of the valve *G* into communication with piston-cylinder *A* and conduit *g*. At the same time the passage *k* is brought into communication between piston-cylinder *B* and the water-exhaust port *V*. At this time the water-case *C* is connected with the steam-exhaust port *W* through the steam-conduit *U*, steam-passage *T*, and conduit *X*. In this position steam-pressure is taken off the valve *l'* and water flows into water-case *C*, and the steam-pressure on the body of water in water-case *D* allows the water to flow by gravitation past valve *o* into the boiler through the boiler-pipe *N*. These operations are automatically and continuously repeated as long as desired.

I prefer to use water instead of steam in the piston-cylinders, as water will prevent

any improper movement, accidental or otherwise, of the pistons and valve H during the operation of the apparatus. Were steam used, it would condense after valve G was 5 shut off and valve H might be moved, accidentally or otherwise; but the presence of a water-body in the piston-cylinder prevents any such accidental or intentional displacement of valve H. Another advantage of water 10 over steam in this connection lies in the fact that it insures an easy movement to the valve H by reason of its escaping gradually from the cylinders. The water forms cushions for the pistons and insures a gradual flow of 15 steam to the water-cases by reason of the gradual opening of valve H. The tanks E and F are valve-controllers in effect and simultaneously move in opposite directions.

In the modification shown in Fig. 5 hollow 20 water and steam conduit floats 1 and 2 are substituted for the tanks E and F. The result obtained by the use of floats as distinguished from balancing-tanks is the same, although the tanks have a tendency to fall; 25 whereas the floats have a tendency to rise; but this difference of tendency is wholly immaterial and floats may be substituted for the tanks, although the tanks are preferable because they are subject to equal pressure 30 inside and out, as will be readily understood by all skilled in the art, whereas floats would be liable to become crushed or destroyed by the steam-pressure and for other causes.

The inner ends of conduits Q, M, L, and P 35 preferably project well above the bottom of water-cases C and D, so as to prevent, in a large measure, sediment at the bottom of the tank getting into the pipes or passing to the boiler.

40 What I claim is—

1. In a boiler-feeder, the combination with the water-cases of a movable valve-controller within each water-case; a pair of pistons and piston-cylinders; conduits from the piston-cylinders; a valve which has a plurality of 45 passages and is so mounted as to control said conduits; mechanism which connects the valve-controllers together and with said valve; and a boiler-conduit extending from said valve; steam and water connections of the cases with the boiler and a valve operated by the pistons.

2. In a boiler-feeder, the combination of 50 water-cases; a pair of piston-cylinders and pistons therefor; a conduit leading from one water-case to the other; said conduit having a port for admission of steam; and a steam-exhaust port; a valve having a plurality of 55 passages and so mounted as to control said conduit connecting the water-cases and also the steam inlet and exhaust ports; and mechanism which connects the pistons together and with said valve; water connections from the cases to the boiler; and the valve controlling the pressure to the pistons operated by connected valve-controllers in the water-cases.

3. The new and useful continuously-feeding boiler-feeder herein described, said feeder comprising, in combination, a plurality of 70 water-cases each having near the bottom a water-inlet and water-outlet; a valve-controller movable within each water-case; a plurality of piston-cylinders; conduits therefor near the inner end of the cylinders; a 75 water-exhaust port; a conduit which connects the upper portion of the water-cases and has a steam-inlet port and a steam-exhaust port; a conduit leading boilerward from the conduits from the piston-cylinders; a valve having a plurality of 80 passages and so mounted that it controls the conduits from the piston-cylinders and the water-exhaust port thereof and the conduit leading boilerward therefrom; mechanism which connects said valve-controllers together and with the valve for the piston-cylinder conduits; pistons in said piston-cylinders; a valve having a plurality of 85 passages and so mounted that it controls not only the conduit connecting the water-cases but also the steam inlet and exhaust ports thereof; and mechanism which connects the pistons together and with the valve for the water-case-connecting conduit.

4. In a boiler-feeder, the combination of 90 water-cases; a movable valve-controller in each case; a piston-conduit; an oscillating valve therefor; a rocker-arm for each valve-controller; a gear near the butt of each rocker-arm; an intermediate gear meshing with said 95 gears on the rocker-arm; an oscillating valve for said piston-conduit; and a gear fast to the oscillating valve and meshing with said intermediate gear; steam and water connections of the cases with the boiler and the valve 100 operated by the pistons for controlling the passage of steam.

5. In a boiler-feeder, the combination of a pair of water-cases; a conduit connecting the same; an oscillating valve in said conduit; a 110 pair of pistons and piston-cylinders; a walking-beam fast to said oscillating valve and connected by each arm with the pistons; a piston-conduit; an oscillating valve therefor; valve-controllers in the water-cases; means 115 for connecting said oscillating valve in the piston-conduit with the valve-controllers, and steam and water connections of the cases with the boiler and a source of supply.

6. In a boiler-feeder, the combination of a 120 conical oscillating valve having a plurality of openings; automatically-operated valve-controllers connected together and with said valve; a supply-pipe with which one of said openings communicates to allow water to operate one piston and to allow water in the other cylinder to flow to the exhaust; a pair of pistons and piston-cylinders; a pair of 125 water-cases; a conduit connecting the cases; a valve in said conduit connected to and operated by the pistons; and steam and water connections from the cases to the boiler.

7. In a boiler-feeder, the combination of a 130 pair of water-cases and a pair of piston-cyl-

inders and pistons therefor; conduits from the piston-cylinders; a valve thereinbetween that alternately communicates with one or the other of said conduits for the piston-cylinders; a conduit from said valve-controlled conduits and in alternate communication through said valve with one or the other of said piston-cylinder conduits; a boiler feed-conduit in communication with the conduit from the piston-cylinder conduits, and water-escape conduits from the water-cases to the

boiler feed-conduit; steam connections to the cases and the valve operated by the pistons.

In testimony whereof I have signed my name to this specification, in the presence of 15 two subscribing witnesses, on this 16th day of February, A. D. 1897.

ANDREW TURNBULL MACCOY.
